CLAIM

The ornamental designs for an elliptical light fixture, as shown and described.

DESCRIPTION

FIG. 1 is a front and bottom isometric view of a first embodiment of an elliptical light fixture embodying my new design;

FIG. 2 is a front view thereof;

FIG. 3 is a left view thereof;

FIG. 4 is a right view thereof;

FIG. 5 is a top view thereof;

FIG. 6 is a bottom view thereof;

FIG. 7 is a rear view thereof;

FIG. 8 is a rear and bottom isometric view thereof;

FIG. 9 is a front view of a second embodiment of an elliptical light fixture embodying my new design and illustrating an elliptical reflector feature visible through the transparent lens; and,

FIG. 10 is a front and bottom isometric view of FIG. 9. The left, right, top, bottom, rear, and rear and bottom views of the embodiment of FIGS. 9 and 10 are identical to FIGS. 3-8, respectively.
